UNITED STATES PATENT OFFICE

153,838

DESIGN FOR A CHILD'S CHAIR

Emerson A. Ward, Detroit, Mich.

Application November 9, 1946, Serial No. 134,674

Term of patent 3½ years

(Cl. D15—8)

To all whom it may concern:

Be it known that I, Emerson A. Ward, a citizen of the United States, residing at Detroit, Wayne County, Michigan, have invented a new, original, and ornamental Design for a Child's Chair, of which the following is a specification, reference being had to the accompanying drawings, forming a part thereof, in which:

Figs. 1, 2 and 3 are the top, front, and side views respectively of a child's chair, embodying the design of the present invention and Fig. 4 is a perspective view thereof.

I claim:

The ornamental design for a child's chair, as shown.

EMERSON A. WARD.
